UNITED STATES. PATENT OFFICE.

PERCY L. SIBOLE, OF SWISSVALE, PENNSYLVANIA.

DIE-CASTING MACHINE.

1,377,604.

Specification of Letters Patent. Patented May 10, 1921.

Application filed March 5, 1920. Serial No. 368,607.

To all whom it may concern:

Be it known that I, PERCY L. SIBOLE, a citizen of the United States, residing at Swissvale, in the county of Allegheny and State of Pennsylvania, have invented new and useful Improvements in Die-Casting Machines, of which the following is a specification.

My invention relates to die casting machines.

The object of this invention is to provide a die casting machine in which the plunger or piston cannot become "frozen" or stuck to the wall of the cylinder in which it works, and to overcome the loss of pressure due to leaky pistons. Other objects appear hereinafter.

Referring to the accompanying drawing, Figure 1 is a central vertical section of a structure embodying one form of my invention, parts being in elevation; Fig. 2, a plan view thereof, and Fig. 3, a section on the line III—III on Fig. 1.

On the drawing, 1 designates a tank composed of any suitable material which does not melt at the temperature of the molten material therein. The tank has in the center of its bottom wall 2 the outlet opening 3, which is continued downwardly by the outlet passage 4 with which the passage 5 communicates, the latter leading to a mold (not shown).

6 is a vertical cylinder having its central opening registering, or in line, with the opening 3 and secured to the bottom 2 by the bolts 7. A non-combustible annular gasket 8 intervenes between the bottom 2 and the bottom of the cylinder. The top of the cylinder supports an annular non-combustible gasket 9, on which is seated the lower head 10, having therein a downwardly tapered opening in axial alignment with the axial center of the cylinder. The screws 10 secure the ring 10 to the cylinder. Above the head 10 is the upper head 11 having therein an upwardly tapering opening also in axial alignment with the axial center of the cylinder. Pins 12 pass through the rings and into the top of the cylinder to guide the upper head and hold it in proper position. The non-combustible packing ring 13 has its opposite ends reversely tapered and seated in the correspondingly tapered openings in the rings. The packing ring is sufficiently thick vertically to keep the heads 10 and 11 spaced apart. The packing may be composed of

various materials but I have found a mixture containing graphite and asbestos to be satisfactory.

14 is a vertical piston or plunger fitting the opening in the packing ring and reciprocable within the cylinder 6. The plunger is made of metal or bakelite, or other suitable non-combustible material, cast on the stem or rod 15 which extends from the bottom of the plunger upwardly through the same and serves as an element to which power may be applied to reciprocate the plunger. The rod is flared at its lower end, as shown at 16, and made larger in diameter just at the top of the cylinder to prevent relative movement of the plunger and the rod.

17 is a cross-bar having its ends connected to opposite portions of the tank by the bolts 18. The cross-bar has the bearing or thimble 19 through which the rod 15 passes. The yoke 20 is secured to the cross-bar 17 by the bolts 21 passing through the feet 22 of the yoke into the cross-bar. The top of the yoke is at some distance above the cross-bar and is provided with an opening which contains the bearing or thimble 23 through which the rod 15 passes. The upper end of the rod has the tongue 24 to which any suitable appliance may be attached for moving the rod up and down.

The plunger 14 has a smaller diameter than the cylinder 6 so that the former cannot engage the cylinder wall or be so close to it as to afford an opportunity for the plunger and cylinder to "freeze" or stick together. If found necessary, lugs 25 may project outwardly from the bottom of the plunger and form a spacing means and a bearing for the plunger against the cylinder wall.

Screws 26 are threaded through the cross-bar 17. They engage the top of the ring 11 for the purpose of adjusting the packing ring 13 to make it fit the plunger tightly. The heads of the screws may be turned by a wrench inserted through the holes 27 in the top member of the yoke 20.

One side of the cylinder 6 has an opening, its outer end constituting a valve seat 28. In horizontal alignment with the said valve-seat opening is the larger threaded opening 29 in the side wall of the tank 1. Into this opening 29 is screwed the stuffing-box 30, through which the valve-stem 31 extends in alignment with the valve-seat opening. The inner end of the stem is shaped to correspond to the shape of the valve-seat 28. The

outer portion of the stem is threaded and works in a threaded hole in the end of the packing cap 32 which is threaded internally and screws on the outer end of the stuffing-box 30. 33 is a non-combustible packing filling the stuffing-box and cap, so that, as the cap is screwed down, it will cause the packing to seal the stem more securely. The outer end of the stem is provided with 10 the operating handle 34.

The valve-stem 31 being on its seat 28, the tank 1 may be supplied with molten metal up to its top, so that the metal is in contact with the outer surface of the cylinder 6, the 15 outer edges of the gaskets 8 and 9, the outer edges of the rings 10 and 11, the opposing faces of the said rings, the upper face of the upper ring 11, portion of the packing ring 13, the upper portion of the plunger 14, and 20 portions of the screws 26. When the stem 31 is backed off by the rotation of the handle 34, the metal in the tank flows past the seat 28 and into the cylinder 6 and the passages 4 and 5. When the cylinder is filled, the handle is turned so as to make the stem 31 close 25 the seat 28, and the rod is operated to cause the plunger to descend and force the molten metal in the cylinder and passages 4 and 5 to enter a mold suitably connected to the 30 passage 5. This operation is well known and need not be further described.

In the prior art, so far as I am aware, no packing ring corresponding to my packing ring 13 has been used; nor has the cylinder 35 been provided with a valved inlet. The plungers have been made of metal ground to fit the interior of the cylinder so closely as to prevent the passage of molten metal past the plunger, or through the inlet opening after the plungers pass the same. With such a close fit of the cylinder and the 40 plunger, the latter would very frequently stick owing to the expansion and contraction of the parts or to a coating of the molten metal adhering to the plunger and the cylinder. I avoid the latter objection by spacing my plunger and cylinder apart so that there is room for free circulation of the 45 molten metal in the space. I prevent leaking of the metal back into the tank by using a valve. I prevent the leaking of the metal past the plunger by using the packing 13.

I claim:

1. In a die casting machine, a tank to contain molten metal, a chamber having its interior in controlled communication with the interior of the tank; a plunger reciprocable through an opening in the chamber and spaced laterally from the chamber, and a 50 packing forming a seal around the plunger and constituting within the opening the only bearing for such parts of the plunger as may come in contact with the molten metal in the chamber.

2. In a die casting machine, a tank to contain molten metal, a chamber having its interior in controlled communication with the interior of the tank, a plunger reciprocable through an opening in the chamber and spaced laterally from the chamber, and a 70 packing closing the opening between the tank and the plunger and adjustable to fit the plunger tightly.

3. In a die casting machine, a tank to contain molten metal, a chamber having its interior in controlled communication with the interior of the tank, a plunger reciprocable through an opening in the chamber and spaced laterally from the chamber, and a 75 packing closing the opening between the tank and the plunger and adjustable to fit the plunger tightly, the packing containing graphite and asbestos.

4. In a die casting machine, a chamber to contain molten metal, and a plunger reciprocable therein and spaced from the wall of the cylinder and a packing surrounding the plunger and forming a bearing therefor and a member spacing the plunger from the 85 sides and cap of the chamber.

5. In a die casting machine, a cylinder to contain molten metal, a plunger reciprocable therein and spaced from the wall of the cylinder, and spaced bearing points carried by the plunger and engaging the wall of the 90 cylinder.

6. In a die casting machine, a cylinder to contain molten metal, and a plunger reciprocable therein and spaced bearings between the cylinder and plunger.

7. In a die casting machine, a tank to contain molten metal, a chamber therein, its interior having a valved connection with the interior of the tank, a plunger reciprocable in the metal in the chamber, a packing preventing the flow of molten metal past the plunger, and means for adjusting the pack- 105 ing.

8. In a die casting machine, a tank to contain molten metal, a chamber therein, its interior having a valved connection with the interior of the tank, a plunger reciprocable in the metal in the chamber, a packing preventing the flow of molten metal past the plunger, and screws for adjusting the pack- 110 ing.

9. In a die casting machine, a tank to contain molten metal, a chamber therein, its interior having a valved connection with the interior of the tank, a plunger reciprocable 120 in the metal in the chamber, a packing preventing the flow of molten metal past the plunger, a cross-bar on the tank, and screws working through the cross-bar and adapted to adjust the packing.

Signed at Pittsburgh, Pa., this 28th day of February, 1920.

PERCY L. SIBOLE.
